US00D748962S

(12) **United States Design Patent**
Newcomb et al.

(10) **Patent No.:** **US D748,962 S**
(45) **Date of Patent:** **** Feb. 9, 2016**

(54) **MEDICAL LAPAROSCOPIC EXTRACTION INSTRUMENT**

(71) Applicant: **CERCORE LLC**, Morrisville, NC (US)

(72) Inventors: **William Levin Newcomb**, Newport News, VA (US); **David Lorin Newcomb**, Morrisville, NC (US); **Stephen Duane Tester**, Cary, NC (US); **Emily JoAnne Newcomb**, Morrisville, NC (US)

(73) Assignee: **Cercore LLC**, Morrisville, NC (US)

(**) Term: **14 Years**

(21) Appl. No.: **29/495,916**

(22) Filed: **Jul. 7, 2014**
